US0D1071467S

(12) **United States Design Patent** (10) **Patent No.:** **US D1,071,467 S**
(45) **Date of Patent:** **** Apr. 15, 2025**

(54) **BOTTLE DRYING RACK**

(71) Applicant: **Li Zhang**, Shenzhen (CN)

(72) Inventor: **Li Zhang**, Shenzhen (CN)

(**) Term: **15 Years**

(21) Appl. No.: **29/955,591**

(22) Filed: **Aug. 2, 2024**

(51) LOC (15) Cl. **07-05**

(52) U.S. Cl.

USPC **D32/58**

(57) **CLAIM**

The ornamental design for a bottle drying rack as shown and described.

DESCRIPTION

FIG. 1 is a perspective view of a bottle drying rack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the bottle drying rack; and,

FIG. 10 is a perspective view of the bottle drying rack where the main body of the bottle drying rack is in a folded state. The broken lines in the drawings depict portions of the bottle drying rack that form no part of the claimed design.

1 Claim, 10 Drawing Sheets
